UNITED STATES PATENT OFFICE.

HARRY B. STILZ, OF BATH, MAINE.

OIL-BURNER.

945,873.

Specification of Letters Patent. Patented Jan. 11, 1910.

Application filed November 18, 1908. Serial No. 463,170.

To all whom it may concern:

Be it known that I, HARRY B. STILZ, a citizen of the United States, residing at Bath, in the county of Sagadahoc and State of Maine, have invented a new and useful Oil-Burner, of which the following is a specification.

My invention relates to improvements in oil burners in which the oil is atomized principally by mechanical means; and the objects of my improvement are, first, to construct a burner which will efficiently burn any of the different kinds of fuel oil used in practice; second, to reduce to a minimum the amount of air or steam used as an atomizing agency, when starting the flame; third, to produce an oil spray, which, when under normal firing conditions will be sufficiently atomized to cause perfect combustion without the aid of an external atomizing fluid, and fourth, to render the system simple and easily accessible for cleaning.

Since it is essential that fuel oil be first partially vaporized before it is suitable for combustion, and that the vaporization be effected with extreme rapidity, the successful burners employ means for breaking the oil into a fine mist or spray, which can readily be acted upon by the heat within the furnace, as well as be intimately mixed with the supply of air for supporting combustion. Nozzles of the centrifugal type, which deliver a jet having a high rate of rotation as well as a rectilinear velocity, cause the issuing fluid to be atomized to such an extent that, when operating in conjunction with an ample supply of air into a furnace with established high temperature, complete combustion is effected. When starting the combustion, however, conditions are such that auxiliary means are useful to bring desired results. At this stage the oil should preferably be diluted with air, steam, or other gaseous fluid, which affords an additional agency for not only inducing a strong current of air supply but also for distributing the atomized oil through a large volume. Rapid evaporation and combustion of the small portion of oil coming into contact with the igniter, generates ample heat to ignite the whole jet and with a high temperature within the furnace and a natural or forced draft once established, the centrifugal action of the jet alone breaks the oil into such fine particles that the external atomizing agency can be reduced to a mini-

mum or, with some varieties of oil, cut off completely without detracting from the efficiency of the flame.

I attain the above objects by the arrangement illustrated in the accompanying drawing in which—

Figure 1 is a sectional elevation through the nozzle and connections at right angles to the axis of the nozzle; Fig. 2 is a section 60 through the axis of the nozzle and Fig. 3 is a plan view of the burner with a part of the furnace shown in section.

The nozzle, composed of an outer casing 1 into which is fitted a center 2, is constructed 70 so as to form an annular space which gradually decreases in diameter to that of the orifice 3 through which the discharge is made. Oil and steam are forced through ports 4 and 5 respectively into this annulus 75 near its largest diameter in a line approximately tangential to the same and in directions as indicated in order to produce a rotation of the fluids therein in a given direction. The areas of the ports 4 and 5 and the 80 orifice 3 are kept small in order that the velocities of rotation and projection may be great, so that the energy producing the same may be effectively utilized for disintegrating the oil. In order to keep the nozzle free of 85 any solid particles which may be present in the oil, a filter is fitted in the oil supply pipe. This filter has a threaded top 7, easily removable, on which is connected a sieve 8 of fine mesh through which the oil is obliged to 90 pass before entering the nozzle. The sieve 8 can easily be cleaned or replaced by a new one by simply disconnecting it from the top 7 around which it is secured. Oil is supplied to the burner through pipe 9 by any 95 suitable means for delivering the oil to the system at the required pressure. Steam is supplied through the pipe 10 from a suitable generator, at a pressure preferably greater than is maintained in the oil pipe and the 100 supply of steam is regulated by the valve 11.

In Fig. 3 the nozzle and filter are shown fastened to plate 12 in front of the furnace 13. The jet is introduced into the furnace through an opening shown in the center of 105 plate 12 and ports 14 for the admission of air are arranged through the channel bar which incloses the space between plate 12 and plate 15 which forms the front of the fire box. In starting a fire, a suitable igniting flame is properly placed within the furnace and oil under a pressure 25 pounds per 110

2

square inch or more is introduced into the nozzle through conduit 9. Steam is likewise admitted to the nozzle through the conduit 10 and the rate of supply controlled by the 5 valve 11. The two fluids mix within the annular space of the nozzle and on issuing from the orifice 3 at a high velocity they induce a strong current of air. When the current of air is supplied to the furnace by 10 either forced or natural draft the supply of steam may be cut off after the combustion has been properly established, the mechanical atomization of the oil alone proving sufficient under these conditions.

15 It will be understood that other gases than steam may be used for the atomizing fluid and that departures from the actual construction, such as a change in the relative positions of the mixing chamber and ports, 20 as well as the number of the latter, can be made without departing from the spirit of the invention for which I claim:

1. A nozzle having an annular space in connection with a concentric orifice, ports 25 leading into said space tangential to said annulus and directed so as to produce rotation in like direction, and conduits for conveying fluid under pressure to said ports.

2. A nozzle having a restricted discharge 30 orifice and independent inlets for a gaseous

fluid and a liquid, there being a passage from each of said inlets to the discharge orifice, said passages having a portion in common which forms a mixing chamber, and each of said passages being arranged to produce a rotary motion in the fluid passing therethrough toward the discharge orifice.

3. A nozzle having an annular space decreasing gradually in diameter and terminating in a small central discharge orifice, there 40 being ports leading into said space at the larger end thereof along lines at an angle to radii extending from the axis, and conduits connected with said ports for delivering thereto an oil and a gaseous fluid under 45 pressure.

4. A nozzle having an annular space in communication with a concentric orifice, there being ports leading into said space along lines at an angle to the radii of the 50 annulus, and directed so as to produce rotation in like direction, conduits for conveying fuel oil and a gaseous fluid under pressure to said ports, and means for closing the conduit for supplying the gaseous fluid.
